UNITED STATES PATENT OFFICE.

MOSES MOSLER, OF CINCINNATI, AND CARL BARTELS, OF HAMILTON, OHIO, ASSIGNEES
TO THE MOSLER SAFE COMPANY, OF NEW YORK, N. Y.

SAFE OR VAULT DOOR.

1,171,348.

Specification of Letters Patent.

Patented Feb. 8, 1916.

Application filed December 24, 1915. Serial No. 68,481.

To all whom it may concern:

Be it known that we, MOSES MOSLER, a citizen of the United States, residing at Cincinnati, Hamilton county, Ohio, and CARL BARTELS, a citizen of the United States, residing at Hamilton, Butler county, Ohio, have invented certain new and useful Improvements in Safe or Vault Doors, of which the following is a specification.

10 This invention, pertaining to improvements in safe or vault doors, relates particularly to the means for joining a bolt-frame of machinable metal to a door of non-machinable metal, such as manganese steel castings, and the invention will be readily understood from the following description taken in connection with the accompanying drawing in which:—

Figure 1 is a section of a door in the plane 20 of lines *a* of Figs. 2 and 3, this figure illustrating an exemplification of our improved door: Fig. 2 a rear elevation of the door, when in square form, parts appearing in vertical section in the plane of line *b* of Fig. 1; and Fig. 3 a rear elevation of the door, when in 25 round form, parts appearing in vertical section in the plane of line *b* of Fig. 1.

In the drawings:—1, illustrates a safe or vault door assumed as being of unmachinable metal, such as manganese steel casting, this door being round, as in Fig. 3, or rectangular, as in Fig. 2, and the margin of the door being provided with the usual steps: 2, an integrally formed rearwardly 35 projecting flange on the door, inwardly of the step of the door: 3, a bolt-frame of machinable metal adapted to the shape of the door and having in its forward portion a groove adapted to engage the flange 2: 40 4, a portion of the bolt-frame projecting inwardly from the grooved portion 3: 5, an inner member of the bolt-frame joined to the inwardly projecting portion 4, by being formed integrally therewith or rigidly 45 secured thereto by any suitable means: and 6, the bolts adapted to slide in and out through suitable apertures in the members

3 and 5 of the bolt-frame, and through flange 2.

In Fig. 2 the door is illustrated as being 50 of rectangular form and in Fig. 3 it is illustrated as being of circular form. Our invention is quite independent of the shape of the door, as regards its outline, and is quite independent of the number of bolts employed, and of the mechanism for operating the bolts, and is quite independent as to any peculiarity of means for securing the bolt-frame to the door. The bolts pass through the members 3 and 5 of the bolt-frame and 55 also through flange 2 of the door. The bolts are to fit the bolt-frame, as usual, and it is immaterial to our invention whether or not the bolts fit the apertures in flange 2 through which they pass. Portion 4 of the 60 bolt-frame, which unites members 3 and 5 of the bolt-frame, will preferably be continued entirely across the inner portion of the door, as illustrated, so as to form a proper seating of machinable metal for the 65 locks and other appurtenances which are to be secured to the inner side of the door.

We claim:—

1. A safe or vault door comprising, a door proper, a flange projecting integrally 75 and rearwardly therefrom, a bolt-frame having a forwardly presenting groove engaging said flange, and bolts slideable through the bolt-frame and flange, combined substantially as set forth. 80

2. A safe or vault door comprising, a door proper, a flange projecting integrally and rearwardly therefrom, a bolt-frame having an outer member provided with a forwardly presenting groove engaging the 85 flange on the door and provided with an inner member united with the outer member, and bolts slideable through the flange of the door and through the inner and outer members of the bolt-frame, combined substantially as set forth. 90

3. A safe or vault door comprising, a door proper, a flange projecting integrally and rearwardly therefrom, an outer bolt-

frame member having a forwardly presenting groove engaging said flange, a bolt-frame member connected with said grooved member and covering the back of the door proper, an inner bolt-frame member connected with the last-mentioned bolt-frame member and disposed inwardly of the grooved bolt-frame member, and bolts slid-

able through the inner member and grooved member of the bolt-frame, combined substantially as set forth.

MOSES MOSLER.
CARL BARTELS.
